UNITED STATES PATENT OFFICE.

SALIM N. MALLOUK, OF BROOKLYN, NEW YORK.

DESIGN FOR AN EMBROIDERED CLOTH BRIDGE-TABLE COVER OR THE LIKE.

Application filed December 28, 1926. Serial No. 20,184. Term of patent 3½ years.

To all whom it may concern:

Be it known that I, SALIM N. MALLOUK, a citizen of the United States of America, and a resident of the borough of Brooklyn, Kings County, city and State of New York, have invented a new, original, and ornamental Design for an Embroidered Cloth Bridge-Table Cover, or the like, of which the following description, in connection with the accompanying drawing, is a specification.

The single figure of the drawing is a plan view of one fourth of an embroidered cloth bridge table cover or the like, showing my new design. The design shown in the representative illustration is repeated in the other three corners.

I claim as my invention:

The ornamental design for an embroidered cloth bridge table cover or the like, substantially as shown and described.

SALIM N. MALLOUK.
